INVENTOR

UNITED STATES PATENT OFFICE.

SALIM N. MALLOUK, OF BROOKLYN, NEW YORK.

DESIGN FOR AN EMBROIDERED LACE SCARF OR THE LIKE.

Application filed June 6, 1929. Serial No. 31,559. Term of patent 7 years.

To all whom it may concern:

Be it known that I, SALIM N. MALLOUK, a citizen of the United States of America, and a resident of the borough of Brooklyn, Kings County, city and State of New York, have invented a new, original, and ornamental Design for Embroidered Lace Scarf or the like, of which the following description, in connection with the accompanying drawing, is a specification.

The single figure of the drawing is a plan view of one half of an embroidered lace scarf or the like, showing my new design. The design shown in the representative illustration is repeated in the other half.

I claim as my invention:

The ornamental design for an embroidered lace scarf or the like as shown and described.

SALIM N. MALLOUK.
